[57] CLAIM

The ornamental design for a vitreous panel for a storm
door or the like, as shown and described.

DESCRIPTION

FIG. 1 is a front elevation of a vitreous panel for a storm
door or the like, in which angular hatching is employed
to indicate transparency of unornamented areas of the
panel, and

FIG. 2 is an enlarged detail of an ornamental figure
which is a component of the design and is repeated
adjacent the corners of the panel embodying the design.
The rear view of the panel is identical with that illus-
trated in FIG. 1, the panel being of conventional thick-
ness.
